(57) **CLAIM**

We claim the ornamental design for a clip, as shown and described.

DESCRIPTION

FIG. 1 is a perspective view of a clip showing our new design viewed from an upper direction;

FIG. 2 is a perspective view thereof viewed from a lower direction;

FIG. 3 is a front elevation view thereof;

FIG. 4 is a right side elevation view thereof;

FIG. 5 is a top plan view thereof;

FIG. 6 is a bottom plan view thereof;

FIG. 7 is a sectional view thereof taken along line 7-7 in FIG. 3;

FIG. 8 is a sectional view thereof taken along line 8-8 in FIG. 4;

FIG. 9 is a first reference view thereof showing the state of use; and,

FIG. 10 is a second reference view thereof showing the state of use.

The broken lines in the drawings are included for the purpose of illustrating environment and form no part of the claimed design.
